UNITED STATES PATENT OFFICE.

R. ELMER GOODRICH, OF NEW HAVEN, CONNECTICUT, ASSIGNOR TO THE
NEW HAVEN CAR TRIMMING COMPANY, OF SAME PLACE.

DESIGN FOR A SASH-LIFTER.

SPECIFICATION forming part of Design No. 12,215, dated April 5, 1881.

Application filed February 19, 1881. Term of patent 3½ years.

To all whom it may concern:

Be it known that I, R. ELMER GOODRICH, of New Haven, in the county of New Haven and State of Connecticut, have invented a new 5 Design for Sash-Lifters; and I do hereby declare the following, when taken in connection with the accompanying drawing, and the letters of reference marked thereon, to be a full, clear, and exact description of the same, and 10 which said drawing constitutes part of this specification, and represents a perspective view.

This invention relates to a design for the article attached to the sash of railway-cars as 15 a means for conveniently raising the sash, and commonly called "sash-lifters;" and it consists in the configuration and ornamentation as shown in the accompanying illustration.

The body A is in the form of a parallelogram, the two ends curved from each side toward the center and outward, the two curves meeting at the center and forming a slightly-projecting point. At the bottom or lower edge

a tongue, B, extends downward, with a termination corresponding to the ends of the body A. From the upper edge of the body the finger-piece C extends forward. The surface of the body A has a quadrant-shaped ornament in each lower corner, consisting of a series of points, with lines extending radially from the angle toward the series of points. At the center of the plate is the representation of a crane standing in water with branches of flag.

I claim—

The herein-described design for sash-lift, 35 consisting of the body A, in the form of a parallelogram, its surface ornamented by a quadrant-shaped figure consisting of a series of points at each lower angle and the representation of a crane at the center, all as shown 40 in the accompanying illustration.

R. ELMER GOODRICH.
